UNITED STATES PATENT OFFICE.

JEROME PRINCE, OF MILFORD, MASSACHUSETTS, ASSIGNOR OF PARTS TO CHARLES E. ALDRICH AND JOHN H. MACDONALD, OF BEVERLY, MASSACHUSETTS.

ELECTRIC TRANSMITTER.

No. 805,092.

Specification of Letters Patent.

Patented Nov. 21, 1905.

Application filed February 2, 1905. Serial No. 243,833.

To all whom it may concern:

Be it known that I, JEROME PRINCE, a citizen of the United States, and a resident of Milford, in the county of Worcester and State 5 of Massachusetts, have invented certain new and useful Improvements in Electric Transmitters, of which the following is a specification.

This invention relates to improvements in 10 telephone-transmitters for telephones, earphones, and other similar purposes; and it consists of the construction and arrangement of parts as will hereinafter be more fully shown and described, reference being had to 15 the accompanying drawings, where—

Figure 1 is a top plan view of the invention, and Fig. 2 is a cross-section on the line 2 2 shown in Fig. 1.

Similar letters refer to similar parts wherever they occur on the different parts of the drawings.

The box is composed of a shell or ring A, to the upper end of which is fitted the open front or mouth piece A'. To the under side 25 of the shell A is fitted the cover A'', as shown. The said box is made of metal, but may be made of hard rubber or other suitable material, if so desired.

B is the vibratory diaphragm, preferably 30 made of aluminium, but may be made of any other suitable material. The periphery of said diaphragm is held in contact with the front A' in any suitable manner. On the inside of said diaphragm B is centrally located 35 a flexible disk C, which may be made of gun-cotton or other suitable flexible material, for a purpose as will hereinafter be stated. On the lower part of said flexible disk is located first a copper disk D, to which is connected a 40 zinc disk E, and to the latter is connected a carbon plate F, as shown in Fig. 2, said parts F, E, D, and C being attached to the diaphragm B by means of a screw-threaded pin G and nut g, as shown in the drawings.

On the interior of the box is located a carbon cup H, containing a carbon disk I, and below the latter a zinc disk K and copper disk L, to which is secured a screw-threaded 45 spindle M, passing through a perforation in the cup H.

Below the carbon cup H is placed a copper disk N, below which is arranged an insulating-sheet O, which may be made of leather, board, or other suitable non-conducting material, interposed between the under side of 55 copper disk N and a perforated hard-rubber ring or washer Q, located in a central recess in the cover A''. The cup H is secured in place within the box by means of the screw-threaded spindle M and a metal nut m, screwed 60 thereon, which nut is insulated from the cover A'' by means of conical bearing-sleeve R, interposed between nut m and the central perforation in the cover A''.

The transmitter is adapted to be connected 65 in a telephone-circuit by means of wires S T in metallic connection, respectively, with the diaphragm B and copper plate K, as shown in Fig. 2.

The carbon cup H contains a granulated 70 mass U, preferably composed of granulated copper, zinc, and magnetic ore, acting as a greater vibratory force for conducting the current. The flexible sheet or washer C serves as a cover around the upper edge of the carbon cup H for the purpose of preventing the 75 granules U from dropping out of said cup.

The device is very simple, composed of 80 very few parts, and provides an excellent and efficient transmitter of increased power when connected in a telephone-circuit either in ordinary telephone or in devices such as are termed "ear-phones," adapted to be carried by persons afflicted with hard hearing or partial deafness.

What I desire to secure by Letters Patent and claim is—

1. The herein-described telephone-transmitter including a casing having a vibratory diaphragm, a flexible disk having copper, zinc 90 and carbon plates coöperative therewith and secured to the diaphragm, a carbon cup having carbon, zinc and copper plates, connected to the interior of said case and arranged opposite said flexible disk, granules interposed 95 between the plates in the respective disk and cup, and circuit-wires connected to the electrode of the transmitter.

2. The herein-described telephone-transmitter including a casing having a vibratory 100

diaphragm, a flexible disk secured thereto and having copper, zinc and carbon plates, a carbon cup oppositely disposed to said flexible disk, carbon, zinc and copper plates within 5 said carbon cup, means for securing the cup to the said case, granules of copper, zinc and magnetic ore interposed between the said plates in the respective disk and cup, and cir-

cuit-wires metallically connected to the electrodes of the transmitter.

In testimony whereof I have affixed my signature in presence of two witnesses.

JEROME PRINCE.
